UNITED STATES PATENT OFFICE.

PAUL PRIEM, OF HEIDENHEIM, GERMANY, ASSIGNOR TO AMERICAN VOITH CONTACT COMPANY, OF NEW YORK, N. Y., A CORPORATION OF NEW YORK.

CENTRIFUGAL SCREEN.

Application filed August 16, 1923. Serial No. 657,651.

To all whom it may concern:

Be it known that I, PAUL PRIEM, a citizen of the Republic of Germany, and resident of Heidenheim a. d. Brenz, Germany, 5 have invented certain new and useful Improvements in Centrifugal Screens, of which the following is a specification.

This invention relates to centrifugal screens for operating on mechanical pulp, 10 chemical pulp, and other stocks mixed with liquids, and has for its main object to complete a screening operation in one machine and to divide the screening effected in one machine into several steps, including both 15 the screening itself and the discharge of the screened stock, so as to obviate the use of pumps necessary in connection with the screening machines heretofore used.

For a double or multiple screen it has 20 been necessary heretofore to arrange the screens on different levels, so that the coarse pulp discharged from one row of machines can be run by natural fall into the following row, where it is diluted with water before being subjected to a repeated screening 25 action.

If the screens are arranged on the same level the coarse pulp discharged from one row must be lifted by means of a pump into 30 the following row of machines. The first arrangement requires an extensive building comprising several stories; the second arrangement requires auxiliary apparatus including pumps and piping.

Both arrangements consume more power 35 than machines constructed according to the present invention where the first and following screening is done in one and the same machine.

40 In the accompanying drawings is shown in vertical longitudinal section an embodiment of my invention.

As illustrated in the drawings, the main frame D¹ of the machine is provided with 45 an inlet A¹ and with a perforated shell A² A³. The shell is also provided with a plurality of chambers or spaces a⁶ a⁸ and separated from each other by means of a transverse partition extending from the 50 main frame to the perforated screen.

The stock to be screened enters into the inlet A¹, which may be of any appropriate shape, and is thrown against said screen by centrifugal action by means of a rotating

runner mounted upon a shaft b² and provided with wings B¹. The shaft b² is journaled in suitable bearings a⁵ and driven by a pulley b³ mounted on said shaft. By means of such operation part of the stock with fibres of a certain grade of fineness 55 passes through the perforations of the shell A², and passes into the annular chamber a⁶, and then discharged therefrom through an outlet a⁷ connected with said chamber or space. The remaining parts of the stock 60 are carried in the direction of the arrow X by means of the runner B¹ and are maintained in a diluted state by means of water jets passing from the apertures of a shower pipe C connected with a suitable source of 65 supply.

The discharge from this shower pipe is spread over the entire inner surface of the perforated shell A³ by means of a mantle b⁴ provided with perforations and attached to 70 the wings of the runner B¹.

The finer parts of the stock pass through the perforations of the shell A³ into the annular space or chamber a⁸ provided with a discharge opening a⁹. The coarser parts 75 which cannot pass through the shell A³ are carried by the action of the runner through an overflow spout a¹⁰, and pass from said spout into the second inlet A¹¹ where the stock is again diluted with water entering 80 the inlet from a suitable source of supply in the direction of the arrow y.

The diluted coarse stock then flows into the inner space of a perforated shell A⁴ 85 where it is subjected to the action of a second runner provided with wings B⁴ mounted upon the shaft b², and is thrown by the runner against the perforated shell A⁴. The fine parts of the stock pass through the perforations of the shell A⁴ into an annular space or chamber formed in the casting and surrounding said shell, and are discharged from said chamber through an outlet a¹² while the remaining coarse stock 95 is carried off from the shell A⁴ through the outlet spout a¹⁴ arranged in the side frame D².

If it is desired to deliver the coarse stock 100 for a second screening operation, the outlet spout a¹⁴ can be arranged more advantageously in a manner similar to the overflow spout a¹⁰ on the upper part of the side frame D². The advantage of such an arrangement 105

consists in the fact that a pump for lifting the stock to a second screen on the same level as the first can be dispensed with.

The perforations of the shell A², A³, 6 and A⁴ may be made of the same size, or of different sizes relatively to each other, according to the grade of pulp to be screened.

In contrast to the known devices heretofore used, the above described invention has 10 the advantage that the separate materials received from the discharge opening a⁷, a⁹, a¹³ are of greater uniformity. Furthermore, the material at its discharge from the opening a¹⁰ is again thoroughly mixed 15 with water by means of the water jet supply pipe C¹, in consequence whereof the fine particles separate themselves better from the coarser particles. In addition thereto, the separate water discharge pipes in the inner 20 part of the round sieve in the described third step through the sieve A⁴, provide a more complete separation or division of the fine material present.

In contrast to the known processes, the advantage of this invention over the prior devices used resides in its greater simplicity; 25 since by the present invention a single machine is used with a single shaft, and only one power transmission is necessary, saving 30 in material, space, and power.

I have described an embodiment of my invention, but it is clear that changes may be made without departing from the scope of the invention as defined in the appended 35 claims.

What I claim as new and desire to secure by Letters Patent is:

1. In a centrifugal screen, the combination 40 of a casing provided with a plurality of chambers arranged axially of said casing, a cylindrical screen forming the inner wall of said chambers, and a runner mounted upon a shaft axially of said screen and provided with wings extending opposite to the wall of 45 said screen and the chambers of said casing.

2. In a centrifugal screen in combination 50 with an outside shell, a shaft with bearings outside of the shell, a runner with wings fastened to the shaft, a second runner of similar design fastened on the same shaft, a perforated shell surrounding each of the runners, means dividing the space between the outside shell and perforated shell into compartments, a stock inlet feeding the stock to 55 be screened to the first runner, and means for transporting the stock from the first runner into the following runner.

3. In a centrifugal screen, in combination 60 with an outside shell, a shaft with bearings outside of the shell, a runner with wings fastened to the shaft, a second runner of similar design fastened on the same shaft, a perforated shell surrounding each of the runners, means dividing the zones between the 65 outside shell and the perforated shell into

compartments, a stock inlet feeding the stock to be screened to the first runner, means for transporting the stock from the first runner into the following runner, and means for diluting the stock before it passes from 70 one zone of the perforated shell into the other.

4. In a centrifugal screen, in combination 75 with an outside shell, a shaft with bearings outside of the shell, a runner with wings fastened to the shaft, a second runner of similar design fastened on the same shaft, a perforated shell surrounding the runners and divided into several zones, a stock inlet feeding the stock to be screened to the first 80 runner, an overflow spout for the stock in the partition wall of the zones of the perforated shell, arranged on the upper part of the screens, and means for transporting the stock to be screened through the overflow 85 spout.

5. In a centrifugal screen, in combination 90 with an outside shell, a shaft with bearings outside of the shell, a runner with wings fastened to the shaft, a second runner of similar design fastened on the same shaft, a perforated shell surrounding the runners and divided into several zones, a stock inlet feeding the stock to be screened to the first runner, an overflow spout for the stock in the 95 partition wall of the zones of the perforated shell, arranged on the upper part of the screen, a second inlet into which the stock is discharged from the overflow spout, and means for discharging the stock through the 100 overflow spout.

6. In a centrifugal screen, in combination 105 with an outside shell, a shaft with bearings on the outside of the shell, a runner with wings fastened on the shaft, a second runner of similar design fastened on the same shaft, a perforated shell surrounding the runners and divided into several zones, a stock inlet feeding the stock to be screened to the first runner, an overflow spout for the 110 stock in the partition wall of the zones of the perforated shell, arranged on the upper part of the screen, a second inlet into which the stock is discharged from the overflow spout, a water connection to the second inlet for diluting the stock, and means for transporting the stock from the overflow spout.

7. In a centrifugal screen, in combination 115 with an outside shell, a shaft with bearings on the outside of the shell, a runner with wings fastened to the shaft, a second runner of similar design fastened on the same shaft, a perforated shell surrounding the runners and divided into several zones, a stock inlet feeding the stock to be screened to the first runner, an overflow spout for the stock in the 120 partition wall of the zones of the perforated shell, arranged on the upper part of the screen, a second inlet into which the 125 stock is discharged from the overflow spout.

stock is discharged from the overflow spout, a water connection to the second inlet for diluting the stock, a discharge spout on the end wall of the last zone of the perforated shell, and means for transporting the coarse stock through this discharge spout.

8. In a centrifugal screen, having a perforated shell, an outer casing divided into different discharging zones, corresponding to different zones of the perforated shell.

9. In a centrifugal screen having a perforated shell, an outer casing divided into different discharging zones, corresponding to different zones of the perforated shell, a rotary blade within the perforated shell, and water supplying means for the rotary blade to enable water to be supplied to the stock and both moved by the blade to zones after and free of the first zone, for diluting the stock discharging against the shell after the first zone.

10. In a centrifugal screen having a per-

forated shell, an outer casing divided into different discharging zones corresponding to different zones of the perforated shells, and 25 separate conduits communicating with the separated zones for conducting away the separated stocks.

11. In a centrifugal screen having a perforated shell, an outer casing divided into 30 separate discharging compartments, with a shell forming one wall thereof, a rotary blade within the shell and casing, a perforated wall movable with the blade and arranged free of the first compartment, and 35 water supplying means for the perforated wall, whereby water is supplied to the stock by said perforated wall after the first compartment.

In testimony that I claim the foregoing 40 as my invention, I have signed by name hereunder.

PAUL PRIEM.
